UNITED STATES PATENT OFFICE.

FREDERICK HACHMANN, OF ST. LOUIS, AND HENRY C. SICKMANN, OF MARTHASVILLE, MISSOURI; SAID HACHMANN ASSIGNOR TO SAID SICKMANN.

COMBINED TIE PLATE AND RAIL JOINT.

Application filed December 12, 1921, Serial No. 521,629. Renewed February 16, 1925.

To all whom it may concern:

Be it known that we, FREDERICK HACHMANN and HENRY C. SICKMANN, citizens of the United States, and residents of the city 5 of St. Louis and State of Missouri, and town of Marthasville, county of Warren, and State of Missouri, respectively, have invented certain new and useful Improvements in Combined Tie Plates and Rail Joints, of 10 which the following is a specification, containing a full, clear, and exact description, reference being had to the accompanying drawings, forming a part hereof.

Our invention relates to improvements in 15 combined tie plates and rail joints, and has for its primary object a rail joint, by means of which the rails can be secured together without the use of bolts and nuts.

A further object is to construct a rail 20 joint in which the fish plates are held against the rails by means of wedges, and in which the joint is also provided with a tie plate which will prevent the meeting ends of the rails from working up and down.

A still further object is to construct a 25 rail joint in which no other tools than a hammer are necessary to secure the meeting ends of the rails in position.

In the drawings,

30 Fig. 1 is an end elevation of our improved device with the rail in position.

Fig. 2 is a top plan view of the same.

Fig. 3 an end elevation of one of the wedge members made use of.

35 Fig. 4 a top plan view of the same.

Fig. 5 a side elevation of the same.

Fig. 6 is a top plan view of the tie plate.

Fig. 7 a longitudinal section on the line 7—7 of Fig. 6.

40 Fig. 8 a cross section on the line 8—8 of Fig. 6.

Fig. 9 a side elevation of one of the fish plates.

45 Fig. 10 an end view of a modified form of fish plate, and Fig. 11 is an end elevation of the fish plate of Fig. 9.

In carrying out our invention we employ 50 a tie plate 11. This tie plate is provided along its edges with notches 12 to receive spikes by which the plate is secured to ties 13. The tie plate is also provided along its center longitudinal line with countersunk spike openings 14 through which spikes may be driven if desired, to secure the plate to 55 the ties, in addition to the spikes used along

the edges. Formed integral with the plate 11 are wedge bases 15 and 16, these wedge bases being inclined horizontally in opposite directions, the wedge base 16 being lowest at the point 17 and highest at the 60 point 18, while the wedge base 15 is lowest at the end 19, and highest at the end 20. Extending toward the center of the plate and formed integral with the ends 17, 18, 19, and 20, are projections 21. These projections are spaced apart, so that the base flange 22 of a railway rail can pass between them. The railway rail is provided with the usual web 23 and ball 24. Located on each side of the web 23 are fish plates 25. These fish plates fit between the wedge bases 15 and 16, and are prevented from moving longitudinally, by means of the projections 21. It will be noted from Fig. 9 that the fish plates have their base flange 26 thicker at 70 the end indicated by the numeral 27, than at the end indicated by the numeral 28. A portion of the base flange of the fish plate is cut away or recessed so that it will engage with the edge of the base flange of the rail. (See Figs. 10 and 11.) The portion 29 of the fish plate engages the web of the rail, while the portion 30 acts as a support for the ball of the rail. Formed integral with the wedge bases 15 and 16 are inwardly extending ribs 31. These ribs also are inclined horizontally, (see Fig. 7) the end 32 being lower than the end 33. These ribs project inwardly at an acute angle and are designed to receive the wedges 34, these wedges being 80 thinner and narrower at the end 35, than at the end 36. The wedges are provided with a vertical face 37 which has formed along its lower edge a bead or rib 38, the opposite face or edge of the wedge being tapered, as indicated by the numeral 39, this taper coinciding with the inclination of the ribs 31. The ribs 31 are braced by means of laterally extending ribs 40, which are formed integral with the ribs, wedge bases and tie plate, and prevent the spreading of the ribs when great force is exerted on them. The rib 38 formed on the wedge members 34 is adapted to fit within the recess 41 formed along the base flange 26 of the fish plates. The purpose of this rib is to preclude any possibility of the wedge tipping after it has been driven home. The installation of our device is as follows:

The tie plate is first placed on the ties and 110

the rails placed in position with the base flanges between the projections 21. The fish plates are then placed on either side of the rail, and between the projections 21. 5 The wedge members 34 are then placed in position and forced in position. After they have been pushed as far as possible, a sledge is employed to drive them in still further. This forces the fish plates tightly against 10 the rail and holds it securely. Due to the downward inclination of the wedges, they are firmly held against accidental jarring loose, due to the travel over the roads. While in the event of rail creeping, the 15 loosening of the wedges is prevented by reason of the fact that the fish plates are held against longitudinal movement by the projections 21 and consequently no longitudinal movement is imparted to the wedges. 20 It will be noted in this connection that only a portion of the wedges rests on the wedge bases 15 and 16, the remainder of the wedges resting on the inclined portion of the base flange of the fish plate, so that the 25 wedges not only force the fish plates against the web of the rail, but also bind them tightly against the base flange.

By the use of our device the meeting ends of the rails are securely held against upward and downward movement, the up-

ward movement being prevented by the fish plates and wedges, while the downward movement is prevented by means of the tie plate. This makes a particularly rigid joint, especially where the meeting edges of 35 the rail happens to come between two ties.

It will also be noted that the modified fish plates are provided with projections 42. These projections are designed to enter bolt holes in the web of the rails and prevent 40 the same from creeping.

Having fully described our invention, what we claim is:

A combined tie plate and rail joint, comprising in combination with a rail, a tie plate, inclined wedge bases formed integral with said plate, inwardly and upwardly projecting ribs formed integral with the wedge bases, projections formed integral with the tie plate and wedge bases, fish plates for 45 securing the rails in position, said fish plates adapted to be held against longitudinal movement by said projections, and wedges tapering in opposite directions located on each side of the rail, and adapted to force 50 the fish plates against the web of the rail.

In testimony whereof, we have signed our names to this specification.

FREDERICK HACHMANN.

HENRY C. SICKMANN.
